GEORGE J. WILLMAN, OF CINCINNATI, OHIO, ASSIGNOR TO THE CINCINNATI ADVERTISING PRODUCTS COMPANY, OF CINCINNATI, OHIO, A CORPORATION OF OHIO

HOLDING MEANS FOR GLASS GLOBES

Application filed December 16, 1931. Serial No. 581,281.

This invention relates to a cushion member adapted for use between a glass globe and the holder or seat normally used with such globes.

5 An object of the invention is to provide a cushion member which will prevent breakage of the globe upon tightening of the retaining screws ordinarily utilized in associating the globe with its holder.

10 Another object is to provide such a member provided with means for resisting the abrasive and wearing action of the retaining screws there-against.

Another object is to provide such a member which totally protects the base portion 15 of the globe from adjacent metal bodies.

Another object is to provide means of the class described which automatically preclude the application of excess pressure upon the globe in associating the latter with its holder.

20 Another object is to provide such a member which is simple in manufacture and in application.

These and other objects are attained by 25 the means described herein and disclosed in the accompanying drawing, in which:

Fig. 1 is a cross-sectional vertical view through a gasoline pump globe and the associated supporting cushion and retaining 30 structure, parts being broken away.

Fig. 2 is a cross-sectional view taken on the line 2—2 of Fig. 1.

It has been a frequent occurrence, heretofore, that the glass globes commonly used 35 upon the top of gasoline pumps, were broken in positioning thereof due to the application of excess or unequal pressure exerted upon the globe when the retaining screws normally associated with the globe holder, were 40 tightened. This result was chiefly due to the fact that the retaining screws were tightened unequally and directly against the base portion of the glass globe whereby the shattering referred to frequently occurred. Inasmuch as glass globes of the kind in question 45 are expensive articles, such mishaps are found to be a considerable item in the accounts of fueling stations and the like. The possibility of such breakage is practically eliminated by 50 the means of the present invention, which in

brief, provides a cushion of rubber or similar yieldable material which is adapted to be interposed between the glass globe and the retaining screws seated in the globe holder. The cushion member itself is further fortified 55 against wear by incorporating therein a metal band co-extensive therewith and adapted to bear the force of the tightened retaining screws. The cushion member is so formed as to snugly embrace the base portion of a 60 glass globe so that the latter is insulated from the metal portions of the holder and other adjacent objects. Further advantages are attained by the use of the means of this invention which will appear in the course of the 65 specification.

The cushion 5 is a split member, annular in shape and comprises the upper enlarged portion 6 having a receding inner face 7, the lower portion of the member being 70 formed into an inwardly projecting flange 8. Incorporated in the enlarged portion 6, and positioned adjacent the outer face thereof, is a metal band 9. It will be observed that the band is co-extensive with the length 75 of the cushion member proper so that when the ends thereof are brought into abutment as in Fig. 2, the ends of the band 9 likewise abut one another to preclude doubling or buckling of the cushion.

80 The inner face 7 and flange 8 of the cushion member are adapted to embrace the base portion 10 of the glass globe 11, the receding face 7 being so formed as to lie snugly against the adjacent curved portion of said base. 85 The globe is adapted to be seated in an annular holder 12 suitably secured upon the top portion 13 of a gasoline pump. The holder 12 is provided with an interior annular seat 14 upon which the base 10 of the 90 globe is adapted to rest. The holder is further formed to provide the upwardly extending wall 15. After the cushion member has been positioned upon the base of the globe, the globe is lowered into its holder until the 95 outer face of the cushion is positioned upon the seat 14, the remaining portion of the outer face of the cushion being in abutment with the inner face of the wall 15. In positioning the globe, the retaining screws 16, 100

normally associated with the wall 15 of the holder, are sufficiently withdrawn to permit the insertion of the globe as described. After such insertion of the globe, the retaining screws 16 are tightened against the outer 5 face of the cushion, the band 9 preventing undue wear upon the gasket and insuring a long period of usage therefor. The tightening of the screws 16 brings the inner face 7 of the cushion into firm contact with the base 10 of the globe, and likewise effects the firm seating of the globe base against the flange 8 of the gasket. The tightening of the screws 16 likewise brings the ends 17 of the cushion member into abutment with one 15 another so that the pressure applied against the globe is equalized and limited by the abutment described. As previously stated the abutment of the ends of the band 9 pre- 20 clude doubling over or buckling of the end portions of the cushion member. In use, the cushion may be shifted slightly upon each removal and replacement of the globe so that the layer of rubber covering the outer face 25 of the band 9 will be evenly worn.

30 The article thus produced is simple and inexpensive in manufacture, eliminates the accidental breakage of glass globes such as described and is by its structure capable of standing long and hard usage.

35 What is claimed is:

1. A cushion member adapted to be positioned between the attachable portion of a light globe or the like and the retaining 40 screws of a holder, said member comprising an elongated body of rubber or like material adapted to embrace the attachable portion of the globe and to have the retaining screws tightened thereagainst, and a metal band im- 45 bedded and enclosed in said body adjacent the outer face thereof and co-extensive in length therewith, said band being adapted to equalize pressure of said screws, and the ends of the cushion member being adapted 50 to abut one another upon tightening of said screws for precluding breaking of the globe by application of excess pressure thereon.

55 2. The combination with a light globe or the like having an attachment base thereon and adapted for association with a base-en- 60 circling holder with globe-retaining screws seated therein, of a cushion member comprising a transversely-split annular body of rubber or like material adapted to be positioned about said base, the upper part of said body being enlarged and formed to snugly embrace the outer face of said base, said upper part being adapted to have said retaining screws tightened thereagainst for positioning said 65 base in the holder, the lower part of said body being formed into an inwardly-turned flange adapted to cover the edge of said base, and a metal band imbedded and enclosed in said upper part adjacent the outer face thereof and coextensive in length therewith, said band be-

ing adapted to equalize pressure on said base upon tightening of the screws and to preclude undue wear of said upper part by said screws, and the ends of the cushion member being adapted to abut one another upon tightening 70 of the screws for preventing excess pressure upon and breaking of the globe.

3. The combination with a light globe hav- 75 ing an attachment base thereon and adapted for association with a base-encircling holder with retaining screws seated therein, of an annular cushion member adapted to embrace the outer face and edge portions of said base and to have said screws tightened there- 80 against for positioning the globe, and means imbedded and enclosed in said member for equalizing pressure of the retaining screws and for precluding breakage of the globe by application of excess pressure of said screws thereon.

4. A cushion member for use with a light globe having an attachment base thereon adapted for association with a base-encircling holder having globe-retaining screws seated transversely therein, said cushion member comprising a transversely split annular body of rubber or the like adapted to embrace the outer face and bottom edge portions of said base and to have said screws tightened against the lateral portions thereof, and an 85 annular metal band coextensive in length with and imbedded in the cushion member op- 90 posite said tightening screws and in right angle relationship with the plane of the screws, said band being adapted to equalize 95 pressure of the tightening screws and reduce wearing of the cushion member by said screws.

In testimony whereof, I have hereunto sub- 100 scribed my name this 14th day of December, 1931.

105 GEORGE J. WILLMAN.
